DISPENSER CAP

James M. Amburgey, Kendall Park, and Livingston C. Douglas, Leonia, N.J., assignors to Colgate-Palmolive Company, New York, N.Y., a corporation of Delaware

Filed Dec. 8, 1964, Ser. No. 82,950

Term of patent 14 years

(Cl. D58—26)

FIG. 1

FIG. 1 is a top plan view of a dispenser cap showing our new design;

FIG. 2 is a front elevational view thereof showing the appearance of the cap in open position; and

FIG. 3 is a back elevational view thereof showing the appearance of the cap in closed position.

We claim:

The ornamental design for a dispenser cap, as shown.
